CARTRIDGE-FEEDING MECHANISM FOR FIREARMS

David M. Williams, New Haven, Conn., assignor to Olin Industries, Inc., New Haven, Conn., a corporation of Delaware

Application October 4, 1947, Serial No. 777,943

7 Claims. (Cl. 42—17)

1

The present invention relates in general to firearms and more especially to improvements in the cartridge-feeding mechanism of a self-loading firearm of the type having a tubular magazine and cartridge-transfer means adapted to automatically transfer a cartridge from the tubular magazine to the chamber of the barrel.

An object of the invention is to provide an improved self-loading firearm which is safe and dependable in operation.

A further object of the invention is to provide a self-loading firearm of the class described with superior cartridge-feeding mechanism wherein cartridges are successively fed automatically from the magazine to the chamber of the barrel without the possibility of jamming or otherwise causing malfunctioning of the firearm.

A still further object of the invention is to provide a self-loading firearm of the class described with superior cartridge-feeding means wherein the breechblock and carrier coact to automatically deliver cartridges successively from the magazine of the firearm onto the carrier free from detrimental effects of recoil.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a fragmentary side elevation partly in section of a self-loading firearm embodying the improved cartridge-feeding mechanism of this invention;

Fig. 2 is an enlarged fragmentary side elevation in section of the firearm of Fig. 1 showing a cartridge in the chamber of the barrel, the breech-block in breech-closing position, and a fresh cartridge extending out of the rear end of the magazine and held securely in this position by coaction of the carrier and the breechblock;

Fig. 3 is a view similar to Fig. 2 but with the cartridge partially extracted from the barrel by the partially-retracted breechblock, the latter and the carrier coacting to release the fresh cartridge onto the forward end of the carrier;

2

Fig. 4 is similar to Fig. 2 but with the breech-block at the end of its rearward excursion, the extracted cartridge having been ejected from the receiver and the fresh cartridge fully supported on the carrier;

Fig. 5 is similar to Fig. 2 but with the breech-block advanced part way forward in the receiver, the fresh cartridge being engaged by the forward end of the breechblock and partially advanced thereby into its chambered position;

Fig. 6 is an end view in section of the firearm on line 6—6 of Fig. 2 illustrating the relationship of the cartridge cutoff to the fresh cartridge which has partially emerged from the rear end of the magazine;

Fig. 7 is a perspective view of the cartridge cutoff;

Fig. 8 is a side elevation of the breechblock showing the improved cartridge-hold-down lug on the underside thereof;

Fig. 9 is a front end elevation of the breech-block;

Fig. 10 is a plan view of the bottom of the breechblock;

Fig. 11 is a plan view of the top of the cartridge-carrier; and

Fig. 12 is a side elevation of the cartridge-carrier.

30 The firearm herein chosen for illustrating the present invention is of the self-loading type in which the barrel is fixed to the receiver and a chamber-extension and breechblock move rearwardly as a unit on the discharge of the firearm,

35 the chamber-extension being adapted to move forwardly thereafter relative to the breechblock and the latter subsequently moving forwardly automatically to insert a fresh cartridge into the chamber of the barrel, as disclosed in my co-

40 pending application Serial No. 733,617 filed March 10, 1947, now Patent Number 2,506,982.

In brief, the firearm includes a receiver 15, a trigger-plate 16 removably mounted in the underside of the receiver adjacent the rear end

45 thereof, a barrel indicated by the reference character 17 secured at its rear end by a threaded connection or the like in an aperture 18 in the front wall 19 of the receiver, a tubular magazine indicated by the reference character 20 and 50 secured at its rear end in an aperture 21 in the

front wall 19 of the receiver and a buttstock indicated generally at 22 suitably secured to the rear wall 23 of the receiver.

Referring to Figs. 2 through 6, the receiver 15 has a top wall 24 and side walls 25 and 26 depending therefrom to form a substantially inverted U-shaped chamber for accommodating the breechblock and the fire-control mechanism. The latter is mounted in the trigger-plate 16 and embodies a pivoted hammer 27 and a trigger indicated generally at 28 for locking and releasing the hammer. Since the fire-control mechanism is not essential to a full disclosure of the invention, further details of this mechanism are omitted. The breechblock or action of the firearm is indicated generally at 29 and is adapted to be supported in the receiver for both longitudinal and pivotal movement therein. To this end, suitable longitudinal guide-grooves 30 and 31 are provided in the inner walls of corresponding sides 25 and 26 of the receiver (see Fig. 6), each guide-groove extending throughout the length of the chamber. Referring particularly to Fig. 6, breechblock-guiding-and-supporting plates 32 and 33 respectively are adapted to be mounted in the corresponding longitudinal guide-grooves 30 and 31 of the receiver and to be connected to the breech-bolt by means of longitudinal ribs 34 and 35 respectively, each being formed on the inner wall of its respective guide-plate and arranged to engage in a longitudinal fantailed groove in the corresponding side of the breechblock. Moreover, each side-plate is provided with a transverse aperture at its rear end, each of which is aligned axially with the other so as to receive a transverse pivot-pin 36. The latter is arranged to extend through suitable rocker-shaped cam-slots 37 formed in the transversely-spaced parallel depending side walls of the breechblock to pivotally connect the latter to the guide-plates 32 and 33. As indicated in Figs. 2 and 6, the right-hand side-plate 33 is also provided with a laterally-extending finger-grip 38 which projects through the ejection-port 39 in the receiver for manually operating the breechblock.

The longitudinal and pivotal movements of the breechblock are controlled in part by means of an operating-link 40, the forward end of which is pivotally connected to the breechblock by the aforesaid transverse pivot-pin 36. The rear end of the operating-link 40 is pivotally connected to the forward end of an inertia-bar 41 which is supported for longitudinal sliding movement in a sleeve 42 which, in turn, is secured to the rear wall 23 of the receiver and extends rearwardly through a longitudinal aperture of the buttstock 22. An action-spring 43 (see Fig. 1) is mounted in an axially-aligned aperture of the buttstock rearwardly of the inertia-bar 41 and is adapted to abut the rear end of the latter to resist rearward displacement thereof; and to return the latter, including the operating-link 40 and breechblock 29, to their respective forward positions in the receiver following the discharge of the firearm.

As pointed out in the application referred to above, the breechblock 29 is adapted to be locked in breech-closing position by engagement of the rear end of its locking-lug 44 with the forwardly-facing shoulder 45 of a longitudinal aperture 46 formed in the top wall of a chamber-extension member 47. The latter constitutes one element of a chamber-unit, indicated generally at 48, which is supported for limited longitudinal movement in the barrel and receiver of the firearm,

the length of movement of the chamber-unit being but a small fraction of the distance moved by the breechblock.

In addition to the usual axially-mounted spring-loaded firing-pin 49 and the extractor 50, the breech-bolt is provided on its underside and at its forward end with an integral downwardly-projecting rib or lug 51 which extends longitudinally of the breechblock and is substantially midway between the opposite sides thereof, as indicated clearly in Fig. 9. The lug 51 constitutes one element of the improved cartridge feeding-means of this invention and to this end, the bottom edge of the lug is formed with a forwardly-and-upwardly-sloping cam-surface 52, a rearwardly-and-upwardly-sloping cam-surface 53 and a substantially-horizontal flat or hold-down surface 54 intermediate the aforesaid forwardly-and-rearwardly-sloping cam-surfaces. The lug 51 of the breechblock is adapted to coact with a cartridge-carrier or elevator, as hereinafter described, to control delivery of fresh cartridges from the open rear end of the magazine onto the carrier.

The cartridge-carrier, indicated generally at 55, is similar to the carrier shown and described in the above identified application, and comprises, briefly, an arm 56 having a cartridge-supporting spoon 57 at its forward end, the arm 56 being an integral rearwardly-projecting extension of the right-hand side of the spoon 57, as indicated clearly in Fig. 11. The carrier-arm 56 is pivotally supported in a vertical longitudinally-extending recess 58 in the right-hand side wall of the trigger-plate by a transverse pivot-pin 59 which extends through the arm forwardly of its rear end on which a carrier-actuating dog 60 is pivotally mounted. The latter is adapted normally to project upwardly and to be held in the path of the lower right-hand edge of the breechblock by a spring 61 which is supported in the vertical recess 58 of the trigger-plate for longitudinal sliding movement therein, whereby the spring 61 functions both as the actuating-spring and as the carrier-spring. In its latter capacity, it is adapted normally to resiliently hold the rear end of the carrier upwardly, whereby its forward end or spoon 57 is held down in a position such that the front edge 62 thereof is slightly below the open rear end of the tubular magazine 20. Moreover, in the present embodiment, the front end of the spoon is provided with a downwardly-and-forwardly-sloping beveled surface or lip 63 which intersects the front edge 62 thereof, while the length of the carrier is such that the front edge 62 of the spoon is located rearwardly of the open rear end of the magazine 20 a distance which may be less than but is preferably slightly greater than one-third the over-all length of the cartridge.

The operation of the carrier by the reciprocating breechblock is fully described in the above identified application and hence it will suffice to say that when the breechblock is in its forward breech-closing position, as shown in Fig. 1, the force of the spring 61 resiliently holds the carrier-spoon down in a position substantially opposite the open rear end of the magazine. Although not shown in the drawings, it will be understood that any of the well known carrier-locking latches may be utilized to positively lock the carrier in this position. Now, as the breechblock moves rearwardly in the receiver, the right-hand bottom edge of the breechblock is adapted initially to ride over the rearwardly-pivoting actu-

ating-dog 50, but on returning from its rearmost position in the receiver to engage with the actuating-dog as indicated in Fig. 4. If, at this time, the carrier is still locked by the aforementioned carrier-latch, then the breechblock will be held adjacent the rear end of the receiver in breech-open position. However, if the carrier-latch has been actuated by a cartridge delivered onto the carrier to release the latter, then the force of the action-return spring 43 will move the breechblock forwardly, mutual engagement of the latter and the actuating-dog acting to depress the rear end of the carrier and elevate its spoon 57, as shown clearly in Fig. 5.

An additional element of the firearm is shown in Fig. 7 and comprises a cartridge-cutoff consisting of a lever-member 64 pivoted on a transverse pivot-pin 65 intermediate its opposite ends in a suitable relief-recess on the inside wall of the left-hand side of the receiver. The forward end of the lever 64 is provided with an inwardly-and-downwardly-projecting toe 66 (see Fig. 6) shaped so as to be substantially concentric to the open rear end of the magazine. Formed on the upper edge of the forward end of the lever is an upwardly-projecting knee 67 which, as indicated in Fig. 2, is located directly beneath the bottom edge of the left-hand side-plate 33 of the breechblock, the knee being adapted to be engaged and held downwardly thereby when the breechblock is in its forward position so as to displace the toe 66 below the lower edge of the open rear end of the tubular magazine and permit egress of cartridge therefrom. The opposite or rear end of the lever-arm 64 is provided with an upwardly-projecting finger 68 which lies substantially in the vertical plane of the knee 67 of the lever-arm. The length of the cutoff-lever is such that the finger 68 will clear the rear end of the side-plate 33 and hence be free to swing upwardly thereby when its toe 66 is depressed. However, as the side-plate 33 and breechblock move rearwardly, the finger 68 is cammed downwardly by the side-plate 33 and so held during the major portion of the rearward and forward excursions thereof, whereby the toe 66 of the cutoff-lever is elevated to prevent egress of a fresh cartridge from the magazine during this interval.

Since the rearmost cartridge in the magazine is released by the cartridge-cutoff lever 64 as the breechblock moves into breech-closing position, it has been customary to provide cartridge stop-means to engage the rearmost cartridge in the magazine and temporarily prevent the cartridge from moving rearwardly onto the carrier, until such time as the breechblock begins its rearward movement in the receiver. Where a depending-lug at the front end of the breech-bolt has been used as a cartridge stop, the released cartridge has been held from rearward movement by abutment against the front edge of this depending-lug.

The present invention has its conception in the discovery that cartridge-stops of this latter type are the indirect, if not the direct, cause of jams and other malfunctioning and that the released and rearmost cartridge of the magazine hereinafter referred to for brevity as the "fresh cartridge" may be restrained from premature rearward movement onto the carrier by coaction of the breechblock-lug 51 and the forward end 92 of the carrier so as to preclude faulty operation of the firearm. In particular, it will be noted on reference to Fig. 2, that the head of

the fresh cartridge is not in abutting engagement with the forward edge of the breechblock-lug 51, but is rearwardly thereof, and in direct engagement with the beveled lip 63 of the carrier, which as pointed out above, permits substantially one-third the length of the fresh cartridge to extend out of the open rear end of the receiver.

Moreover, the fresh cartridge is securely held in contact with the beveled lip 63 of the carrier by a jamming action effected by the flat or hold-down surface 54 of the lug 51, which engages on the top of the rearwardly-projecting portion of the fresh cartridge and positively holds the latter and more especially its rim from riding upwardly and rearwardly on the beveled lip of the carrier. In this connection, it should be emphasized that the hold-down action of the breechblock-lug 51 is effectively maintained both while the breechblock is locked in breech-closing position and during an appreciable length of its rearward excursion following discharge of the firearm, which length corresponds to substantially one-third the length of the cartridge, as indicated clearly in Fig. 3. Thus, a relatively-long delay is introduced between the time the breechblock begins its rearward movement and the subsequent rearward movement of the fresh cartridge. For guns of this class having a fixed barrel and reciprocable breechblock, this delay is a major factor in insuring smooth and dependable operation.

An additional function of the breechblock-lug 51 is that of preventing the adverse effect of recoil on the fresh cartridge when the firearm is discharged. Normally, the effect of recoil is to slide the rearmost cartridge in the magazine forwardly and heretofore it has happened not infrequently that the rearmost or fresh cartridge about to be delivered onto the carrier has been moved forwardly sufficiently into the magazine so as to be caught by the cartridge cutoff, thereby interrupting the normal automatic action of the firearm.

The hold-down surface 54 of the improved breechblock-lug 51 of this invention provides both frictional and positive means to restrain the fresh cartridge from moving forwardly into the magazine on discharge of the firearm, the frictional restraint being effected by direct contact of the hold-down surface 54 with the upper surface of the cartridge; and the positive restraint being effected by engagement of the rim of the cartridge-head with the rearwardly-and-upwardly-sloping cam-surface 53 of the lug. Thus, assuming the recoil force was sufficiently great to overcome the counteracting force of the magazine-spring 69 and the frictional restraint offered by engagement of the hold-down surface 54 of the lug 51 with the upper surface of the cartridge, then the latter would move forwardly until its rim struck against the rearwardly-and-upwardly-sloping cam-surface 53. However, since the breechblock would be moving rearwardly, the rearwardly-moving cam-surface 53 of the lug 51 would positively counteract the forward movement of the cartridge and thus prevent the latter from ever engaging the cartridge cutoff.

Referring particularly to Figs. 2 and 3, it will be seen that the foregoing conditions exist when the breechblock is in breech-closing position and during the relatively-short interval following the discharge of the firearm in which the breechblock is unlocked from the chamber-extension

47 and moves rearwardly a distance corresponding substantially to the distance from the point of engagement of its lug 51 with the top surface of the cartridge to the cartridge-rim at the rear end thereof.

As the breechblock continues its rearward movement, the breechblock-lug 51 is brought opposite the rear end of the shell, whereupon the rearwardly-sloping cam-surface 53 of the lug cams the rim of the cartridge-head downwardly and slightly forwardly on the beveled lip 63 of the carrier, thus permitting the hold-down surface 54 of the lug to pass over the rim of the cartridge. Thereafter, as the forwardly-and-upwardly-inclined cam-surface 52 of the lug moves away from the cartridge-rim, the hold-down force directed downwardly thereon by the bolt-lug is gradually released, whereupon the cartridge, and in particular its rim, is free to move upwardly and rearwardly on the beveled lip 63 of the carrier and thereafter rearwardly onto the carrier-spoon, both the upward and rearward movement of the cartridge on the carrier-lip 63 and its subsequent rearward movement onto the spoon being effected by the rearwardly-acting force of the magazine-spring 69.

Thus, the fresh cartridge follows the breechblock rearwardly in the receiver but in all likelihood at a somewhat slower rate. Moreover, due to the aforesaid delay in starting, any possibility of the fresh cartridge running ahead of or so close behind the breechblock as to cause a jam by releasing the carrier before the fired cartridge has been ejected, is avoided. When a fresh cartridge does arrive at its fully-supported position on the spoon of the carrier, the latter is adapted to be unlocked as, for example, by a cartridge-actuated latch (not shown), whereupon the force of the action-return spring 43 urges the breechblock forwardly, thereby depressing the rear end of the carrier through the medium of its actuating-dog 68 and elevating its forward end or spoon (see Fig. 5) to bring the fresh cartridge thereon up into a position in front of the face of the breech-bolt, whereby as the latter advances, it engages and chambers the fresh shell in the barrel of the firearm.

Just before the breechblock arrives in chamber-closing position, the knee 67 of the cartridge-cutoff lever will be engaged by the bottom edge of the left-hand side-plate 33 and pivoted downwardly so as to withdraw the toe 66 from out of the bore of the tubular magazine, thereby releasing the next-succeeding rearmost cartridge therein. The latter is promptly thrust rearwardly from the open rear end of the magazine by the force of the magazine-spring 69 and brings up against the forwardly-and-upwardly-sloping cam-surface 52 of the forwardly-moving breechblock-lug 51 which momentarily depresses the cartridge as it rides over the rim thereof. Immediately thereafter the hold-down surface 54 of the lug 51 will engage the top side of the cartridge forwardly of its rim, thereby pressing or jamming its rim down firmly in engagement with the beveled lip 63 of the carrier so as to preclude further rearward movement of the cartridge.

It will be appreciated from the foregoing description and the drawings, that coaction of the breech-bolt lug with the cartridge-carrier provides cartridge-feeding means which affords a slight delay between the time the breech-bolt begins its rearward movement and the subsequent follow-up of the fresh cartridge. This

delay insures the successful extraction and ejection of the fired cartridge from the receiver before the fresh cartridge can be elevated into position to interfere with or jam the fired cartridge. Although such circumstance is somewhat remote in firearms of the class having a recoiling barrel, the likelihood of jams occurring due to this cause in firearms having a stationary or fixed barrel is great. Moreover, by exerting a positive downwardly-directed force on the top side of the rearmost cartridge in the open rear end of the magazine so as to jam the rear end of the cartridge against the beveled front end of the carrier, the cartridge is positively held against premature rearward movement.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a self-loading firearm, the combination including: a receiver having a chamber; a barrel mounted on the forward end of said receiver; a tubular magazine supported beneath said barrel, said tubular magazine having an open rear end intersecting the forward end of said chamber and a magazine-spring arranged to project the rearmost cartridge in said magazine from the open rear end thereof into said chamber; a breechblock reciprocably mounted in said chamber; a cartridge-carrier pivotally mounted in said chamber; carrier-actuating means arranged to hold the forward end of said carrier normally opposite the open rear end of said magazine when said breechblock is in the forward end of said chamber; and means to control a cartridge projected onto said carrier from said magazine when said carrier is in its normal position, said control-means comprising a lip on the forward end of said carrier and an element mounted on said breechblock forwardly of said lip when the breechblock is in breech-closing position arranged to engage the top side of the cartridge substantially intermediate the opposite ends thereof to hold said cartridge in engagement with the lip of said carrier on recoil of said firearm.

2. In a self-loading firearm, the combination including: a receiver having a chamber; a barrel mounted on the forward end of said receiver; a tubular magazine supported beneath said barrel, said tubular magazine having an open rear end intersecting the forward end of said chamber and a magazine-spring arranged to project the rearmost cartridge in said magazine from the open rear end thereof into said chamber; a breechblock reciprocably mounted in said chamber; a cartridge-carrier pivotally mounted in said chamber; carrier-actuating means arranged to hold the forward end of said carrier normally opposite the open rear end of said magazine when said breechblock is in the forward end of said chamber; and means to control a cartridge projected onto said carrier from said magazine when said carrier is in its normal position, said control-means comprising a beveled lip on the forward end of said carrier and a lug on the underside of said breechblock forwardly of said lip when the breechblock is in breech-closing position, said lug having a hold-down surface on its bottom edge arranged to engage the top side of the car-

tridge forwardly of its rim thereby to hold said cartridge from moving forwardly out of engagement with the beveled lip of said carrier on recoil of said firearm.

3. In a self-loading firearm, the combination including a receiver having a chamber; a barrel mounted on the forward end of said receiver; a tubular magazine supported beneath said barrel, said tubular magazine having an open rear end intersecting the forward end of said chamber and a magazine-spring arranged to project the rearmost cartridge in said magazine from the open rear end thereof into said chamber; a breechblock reciprocably mounted in said chamber; a cartridge-carrier pivotally mounted in said chamber; carrier-actuating means arranged to hold the forward end of said carrier normally opposite the open rear end of said magazine when said breechblock is in the forward end of said chamber; and means to control a cartridge projected onto said carrier from said magazine when said carrier is in its normal position, said control-means comprising a beveled lip on the forward end of said carrier and a lug on the underside of said breechblock forwardly of said lip when the breechblock is in breech-closing position, said lug having a hold-down surface on its bottom edge arranged to engage the top side of the cartridge forwardly of its rim thereby to hold said cartridge from moving forwardly out of engagement with the beveled lip of said carrier on recoil of said firearm, and an upwardly-and-rearwardly-sloping cam-surface on the bottom edge of said lug arranged to engage and depress the rim of said cartridge during the rearward movement of said breechblock relative to said held cartridge so as to permit said hold-down surface to ride thereover.

4. In a self-loading firearm, the combination including: a receiver having a chamber; a barrel mounted on the forward end of said receiver; a tubular magazine supported beneath said barrel, said tubular magazine having an open rear end intersecting the forward end of said chamber and a magazine-spring arranged to project the rearmost cartridge in said magazine from the open rear end thereof into said chamber; a breechblock reciprocably mounted in said chamber; a cartridge-carrier pivotally mounted in said chamber; carrier-actuating means arranged to hold the forward end of said carrier normally opposite the open rear end of said magazine when said breechblock is in the forward end of said chamber; and means to control a cartridge projected onto said carrier from said magazine when said carrier is in its normal position, said control-means comprising a beveled lip on the forward end of said carrier and a lug on the underside of said breechblock forwardly of said lip when the breechblock is in breech-closing position, said lug having a hold-down surface on its bottom edge arranged to engage the top side of the cartridge forwardly of its rim thereby to hold said cartridge from moving forwardly out of engagement with the beveled lip of said carrier on recoil of said firearm, and an upwardly-and-forwardly-sloping cam-surface on the bottom edge of said lug arranged to release said held cartridge for rearward movement onto said carrier by said magazine-spring as said breechblock moves rearwardly relative thereto.

5. In a self-loading firearm, the combination including: a receiver having a chamber; a barrel mounted on the forward end of said receiver; a tubular magazine supported beneath said barrel,

said tubular magazine having an open rear end intersecting the forward end of said chamber and a magazine-spring arranged to project the rearmost cartridge in said magazine from the open rear end thereof into said chamber; a breechblock reciprocably mounted in said chamber; a cartridge-carrier pivotally mounted in said chamber; carrier-actuating means arranged to hold the forward end of said carrier normally opposite the open rear end of said magazine when said breechblock is in the forward end of said chamber; and means to control a cartridge projected onto said carrier from said magazine when said breechblock is in the forward end of said chamber, said control-means comprising a beveled lip on the forward end of said carrier and a lug on the underside of said breechblock forwardly of said lip when the breechblock is in breech-closing position, said lug having a substantially-flat hold-down surface on its bottom edge arranged to engage the top side of the cartridge forwardly of its rim thereby to hold said cartridge from moving forwardly out of engagement with the beveled lip of said carrier, an upwardly-and-rearwardly-sloping cam-surface on the bottom edge of said lug rearwardly of said flat hold-down surface arranged to engage and depress the rim of said held cartridge, so as to permit said flat hold-down surface to ride thereover during the rearward movement of said breechblock relative to said cartridge, and an upwardly-and-forwardly-sloping cam-surface on the bottom edge of said lug forwardly of said flat hold-down surface arranged to release said held cartridge for rearward movement onto said carrier by said magazine-spring as said breechblock moves rearwardly relative thereto.

6. In a self-loading firearm, the combination including: a receiver having a chamber; a barrel mounted on the forward end of said receiver; a tubular magazine supported beneath said barrel, said tubular magazine having an open rear end intersecting the forward end of said chamber and a magazine-spring arranged to project the rearmost cartridge in said magazine from the open rear end thereof into said chamber; a breechblock reciprocably mounted in said chamber; and means to hold the cartridge projecting into said chamber from said magazine from moving forwardly into said magazine when said firearm is discharged, said cartridge-holding means comprising an element on said breechblock arranged to project downwardly from the underside thereof to frictionally engage the top side of said cartridge intermediate its opposite ends when the breechblock is in breech-closing position.

7. In a self-loading firearm, the combination including: a receiver having a chamber; a barrel mounted on the forward end of said receiver; a tubular magazine supported beneath said barrel having an open rear end intersecting the forward end of said chamber and a magazine-spring arranged to project the rearmost cartridge in said magazine from the open rear end thereof into said chamber; a breechblock reciprocably mounted in said chamber; a cartridge-carrier pivotally mounted in said chamber; carrier-actuating means arranged to hold the forward end of said carrier opposite the open rear end of said magazine; means to hold the cartridge projecting into said chamber from said magazine from moving forwardly into said magazine when said firearm is discharged, said cartridge-holding means comprising a lug projecting from the

underside of said breechblock, said lug having a flat hold-down surface arranged to engage the cartridge forwardly of the rim thereof when the breechblock is in breech-closing position; and a rearwardly-and-upwardly-inclined cam-surface arranged to engage the rim of said cartridge to depress said rim below said hold-down surface during the rearward movement of said breechblock relative to said cartridge so as to permit said hold-down surface to pass over the rim thereof.
